Inventor:
John Bryant

United States Patent Office.

JOHN BRYAN, OF LEBANON, ILLINOIS.

Letters Patent No. 90,921, dated June 8, 1869.

IMPROVEMENT IN MACHINE FOR PLOWING AND BREAKING UP GROUND.

The Schedule referred to in these Letters Patent and making part of the same.

Be it known that I, JOHN BRYAN, of Lebanon, in the county of St. Clair, and State of Illinois, have invented an Improved Machine for Breaking Ground and Cultivating Corn; and I do hereby declare that the following is a full, clear, and exact description of the same, reference being had to the annexed drawings, making a part of this specification, in which—

Figure 1 is a side view.

Figure 2 is a top view.

A A A, hounds.

B B, beams.

C, double-trees.

D D, wheels.

E E, spindle, or axle.

F F, upright piece, to which spindle is bolted.

G G, hind levers.

H H, gearings.

i i, forward lever.

J J, frame.

K, brace.

The hounds A A A work on a pivot; which arrangement allows the plows to run steady and even, when plowing uneven ground.

H H, the gearing, or pivot-joints by which the beams are attached, hold the plows in an upright position, yet allow them to turn sideways or raise up or down.

The wheels may be set back or forward, as required, to balance weight of driver or plows when raised, by moving upright F to forward corner of frame.

Wheels D D may be raised or lowered by slit e e in the casting of the spindle.

The hind cross-piece of frame J may be set angling, as represented by dots on drawings.

What I claim as my invention, and desire to secure by Letters Patent, is—

1. The pivoted frame or hounds A A, in combination with the plow-beams and main-frame J J, as constructed and arranged.

2. The lever and link i i, in combination with the hounds A A, and main-frame J, as shown.

JOHN BRYAN.
